UNITED STATES PATENT OFFICE.

WILLIAM H. KREMER, OF OAK PARK, ILLINOIS.

DESIGN FOR A BROOM AND DUST-PAN HANGER.

41,319.

Specification for Design.

Patented Apr. 18, 1911.

Application filed January 23, 1911. Serial No. 604,278. Term of patent 3½ years.

To all whom it may concern:

Be it known that I, WILLIAM H. KREMER, citizen of the United States, residing at Oak Park, in the county of Cook and State of Illinois, have invented and produced a new, original, and ornamental Design for a Broom and Dust-Pan Hanger, of which the following is a specification, reference being had to the accompanying drawing, forming a part hereof.

This invention has for its object to provide a novel and ornamental design for a broom and dust pan hanger.

The accompanying drawing illustrating my design shows a broom hanger embodying the same in perspective view.

The novelty of the design resides in the particular formation of the plate wherein there is formed a panel bordered by the raised framing beveled on its edges, and in the form of the projecting member attached to the frame portion of the plate below the panel, the whole being very ornamental and artistic in appearance.

I claim:

The ornamental design for a broom and dust pan hanger as shown and described.

WILLIAM H. KREMER.
